BOTTLE.

1,223,351.

Specification of Letters Patent.

Patented Apr. 24, 1917.

Application filed October 14, 1915. Serial No. 55,841.

To all whom it may concern:

Be it known that I, BERTHA S. ALSOP, a citizen of the United States of America, residing at New York city, New York, have 5 invented a new and useful Bottle, of which the following is a specification.

The object of this invention is to provide in simple and practical form, a bottle construction which will prevent refilling of the 10 bottle by any ordinary means, and which, if, by any possibility is refilled, will prevent the contents of the bottle being used.

Other and more specific objects are to provide a simpler and more effective form of 15 valve, and to provide a simple and efficient form of lock for automatically securing the valve construction in the bottle neck.

In accordance with my invention the valve parts are mounted within a tubular member 20 which is inserted within the bottle neck and which is held in place therein by a transversely extending locking pin which engages beneath an internal shoulder on the 25 bottle neck. This tubular valve-carrying member has an outlet passage for the liquid, and a valve seat surrounding said passage. The valve normally rests upon this valve seat, but is displaceable down into the outlet passage upon the application of pressure 30 thereto. A loose weight may be mounted above the valve for normally holding the valve in engagement with the seat, and a special feature of this weight or guard is that it carries means coöperating with the 35 valve to hold said valve, when displaced, down in the outlet passage.

Other features and the details of construction, including the novel construction 40 of the valve, will appear as the specification proceeds.

In the accompanying drawing, I have illustrated a practical and preferred embodiment of my invention, but it will be understood that various changes and modifications 45 may be made without departing from the true spirit or scope of the invention.

In this drawing:

Figure 1 is a vertical sectional view of the upper part of a bottle neck having my 50 invention incorporated therein. This view illustrates the position of the locking device as the valve mechanism is being inserted in the bottle neck.

Fig. 2 is a similar sectional view showing

the parts in the pouring position. In this 55 view the locking device is shown in its final position interlocked beneath the shoulder on the inside of the bottle neck, and a finishing collar is shown around the rim of the bottle neck.

Fig. 3 is a cross sectional view taken substantially on the plane of the line 3—3 of Fig. 1.

Fig. 4 is a diagrammatic view illustrating two displaced positions of the valve, 65 and illustrating the means preventing reengagement of the displaced valve with the valve seat.

Fig. 5 is a similar view of a slightly modified form of construction.

Fig. 6 is another diagrammatic view of the invention embodied in another form.

In the first four views the invention is shown applied to a bottle which is of ordinary construction, except that it is provided 75 with an internal shoulder 10 in the neck portion 11 thereof and disposed at some distance inward from the mouth of said neck portion. This shoulder provides an abutment against which a locking pin 12 engages 80 to secure the valve mechanism within the bottle neck. The engagement of this locking pin beneath the locking shoulder is illustrated in Figs. 2 and 4 and as there indicated, it will be seen that this locking shoulder need not be an abrupt shoulder but may be merely in the form of a gradual swelling, 85 on the inside of the bottle neck.

The various parts of the valve mechanism are mounted within and carried by a tubular 90 supporting member 15, having an outlet passage 16 and a valve seat 17 at the upper end of and surrounding said passage. This tubular supporting member when in place in the bottle neck extends down into the bottle 95 neck to a point below the internal locking shoulder 10 and is there provided with an internal recess 18 in one wall, and with a longitudinal slot 19 in the opposite wall, this recess and slot being provided to receive 100 the transversely extending locking pin 12.

The action of the locking pin will be understood from Figs. 1 and 2. This pin, which may be in the form simply of a straight piece of glass rod of the proper 105 length, engages in the recess 18 at one end and projects across the passage 16 out through the slot 19 in the opposite wall. As

the valve-carrying member is inserted in the bottle neck, as indicated in Fig. 1, the projecting end of the locking pin engages with the inner surface of the bottle neck and, as it 5 rides over the upper surface of the locking shoulder, yields upwardly in the slot 19 until the tubular member passes far enough into the bottle neck to permit it dropping down into position beneath the locking shoulder. When 10 the locking pin has been thus engaged beneath the locking shoulder, as shown in Fig. 2, it prevents the valve-carrying member being withdrawn from the bottle neck. This pin is preferably made long enough to engage 15 with the inner wall of the neck beneath the shoulder substantially as shown.

To force the locking pin downward in its 20 guide slot 19, and so insure the engagement of the locking pin beneath the locking shoulder, a spring may be provided such as that indicated, consisting of a flat piece of cork seated in a groove 21 in the outer surface of the tubular supporting member bearing on top of the projecting end of the locking 25 pin and arranged to bulge outwardly as indicated in Fig. 1, as the device is being inserted in the bottle neck. This cork strip or other spring element which may be employed, exerts its force to press the locking 30 pin downwardly in the slot, and serves in the final position indicated in Fig. 2, to hold the locking pin against rattling in case there is any lost motion at this point.

The valve member in the preferred embodiment is made up of four parts, a body 35 25, a flat disk-like flexible member 26, a reinforcing washer 27 and a float 28. These parts are arranged in the order named, the valve disk lying on top of the valve body, 40 the reinforcing washer being secured on top of the valve disk, and the float being secured on top of the reinforcing washer. These valve parts are secured together by any suitable means, in the first form illustrated, by 45 providing an upstanding headed stud which extends through openings provided in the valve disk and reinforcing washer and engages in the material of the float.

The valve body is preferably made of a 50 relatively hard glass-like material so as to give weight and stability to the valve and is made of a size to have an easy sliding fit in the passage 16. This fit may be obtained and without the danger of binding in the 55 passage by providing the valve body with dependent projections or fingers 30 around the rim thereof. The valve disk extends out beyond the edges of the valve body far enough to firmly engage the valve seat and 60 the valve body serves to hold said disk centered in respect to the valve seat.

The valve disk may be made of any suitable flexible liquid-proof material. I have found sharkskin a very practical and desirable material for this purpose.

The reinforcing washer is preferably made of a yieldable though relatively stiff material and of a size to just fit within the outlet passage. I have found cork an excellent material for this purpose.

70

The float may be made of any suitable material having sufficient buoyancy or the buoyancy may be obtained by making the float in hollow form. In the illustration I use a cork body for the float which may be tapering in form like an ordinary commercial cork, and of a size to fit loosely within the outlet passage. One advantage of the cork float is that the valves parts may be secured together by simply forcing the headed 75 stud 29 of the valve body firmly into the cork.

75

The valve is normally held to its seat by gravity and additional means for this purpose may be provided in the form of a hollow weight 32, which receives the upper float portion of the valve, and serves by engagement therewith to hold the valve downward against its seat. The lower rim of this hollow weight and guard may be beveled 80 upwardly and inwardly from the outer edge thereof as indicated at 33 so as not to bear upon the valve disk and it is further preferably provided with an opening 31 in the top and an opening 34 in the side thereof. 85

80

Access to the valve and the valve closing weight are preferably provided against by means of a guard such as that indicated at 90 and consisting of a transverse partition around which liquid ports 36 are provided. 100 It will be evident that the construction disclosed provides a practically non-refillable bottle. The only way in fact that any liquid can be forced into the bottle, is by the application of excessive pressure. This pressure, 105 on account of the flexibility of the valve disk, forces the disk down into the outlet passage 16 and thereby destroys its usefulness as a valve, said valve ordinarily under such circumstances binding in the passage 110 and completely closing the same. The reuse of the valve though, is positively guarded against in the present disclosure, by providing means carried by the movable guard 32 and coöperating with the valve 115 when thus displaced to prevent its reengagement with the valve seat. This means consists in the form illustrated in Figs. 1 to 4, of a loose piece 40 normally seated in a pocket 41, in the under side of the top of 120 the movable guard and arranged to drop down out of said pocket in the top of said valve when the valve has once been displaced. This condition is illustrated in Fig. 4. By making this loose piece relatively 125 long in the form of a rod and by making the pocket which receives it comparatively narrow, it will be evident that it will be practically impossible once said piece has been displaced from the pocket to shake it 130

120

125

130

back into place therein. The said piece, therefore, constitutes a very effective lock for preventing reengagement of the displaced valve with the valve seat. The flow 5 of liquid through the hole 31 in the top of the guard actuates the locking bar 40 when the valve is forced with the bottle in inverted position and the hole 34 (in the side of the guard) prevents the guard holding 10 enough liquid to float the valve to its seat, when pouring.

Another very simple form of lock for the valve is that illustrated in Fig. 5 and consisting of an upstanding stud 43 on top of the valve, normally engaged in a passage 44 in the top of the movable guard. This 15 passage is just large enough to receive the stud 43 and when once the stud is disengaged from the passage by the displacement 20 of the valve, it is a practical impossibility to again reengage said stud in the passage.

The valve is brought into operative relation with its valve seat usually by forcing the valve upward through the passage 16 25 in the manner indicated in Fig. 5. Once the parts are properly assembled, as indicated in Fig. 4, it will be seen that it will be impossible to force the valve down and out of the outlet passage because the transversely 30 extending locking pin 12 will act as a stop limiting the downward movement of the valve.

In Fig. 5 I have shown how the parts of the valve may be secured together by means 35 of a pin 45 passed through the several parts of the valve. This pin may be of wood so that it will swell by contact with the liquid and so hold the parts all the more firmly together. This securing pin may be extended 40 far enough up, as indicated, to serve as the stud for preventing the reengagement of the displaced valve with its valve seat.

A cork or the like gasket 47 may be provided to hold the valve-carrying device centrally located in the bottle neck and to prevent leakage of the liquid between the edges of said device and the sides of the bottle neck.

The mouth of the bottle may be finished 50 off with a ring 48 around the rim of the neck and engaging over the rim of the valve-carrying device, substantially as indicated in Fig. 2.

One advantage of the form of the invention thus far disclosed is that it can be made 55 relatively small in size so as to be insertible into a bottle neck of the usual size. In the form of the device illustrated in Fig. 6 the valve-carrying member is secured by an annular securing ring 50 on top of the upper edge of the bottle neck 51. The valve seat is 60 in this case provided by an annular washer like member 52 which has a dependent portion 53 providing the outlet passage 54. The other parts are similar to those already 65

described except that in this case the cork float 28' is large enough at its top to engage the valve seat and prevent the valve being forced down into the bottle upon the application of excessive force. When the valve is thus displaced the valve disk 26' will engage beneath the lower edge of the dependent portion 53 and thereby prevent the valve being reengaged with its valve seat. 70

What I claim is:

1. In a non-reusable bottle, a bottle neck having an outlet passage and a valve seat surrounding said outlet passage, a valve normally engaging said valve seat and displaceable by pressure into said outlet passage, a guard above the valve and means carried by said guard and coöperating with the valve upon displacement of the valve into the passage to prevent reengagement of the valve with the valve seat. 75

2. In a non-reusable bottle, a bottle neck having an outlet passage and a valve seat surrounding said outlet passage, a valve normally resting upon said valve seat and displaceable into the outlet passage upon the application of pressure thereto, a weight above the valve for holding said valve engaged with the valve seat, and means carried by said weight and coöperating with the valve upon displacement of the same into the passage to prevent reengagement of the valve with the valve seat. 80 90 95

3. In a non-reusable bottle, a bottle neck having an outlet passage and a valve seat surrounding said passage, a loose hollow weight above the valve seat, a valve received in said hollow weight and normally engaging the valve seat but displaceable down into the outlet passage upon application of pressure thereto and coöperating means on the top of the valve and the inside of the hollow weight engaging upon displacement of the valve down into the outlet passage to prevent said valve being returned into engagement with the valve seat. 100 105 110

4. In a bottle construction, a bottle neck having an outlet passage and a valve seat surrounding said passage, and a valve for coöperation with said valve seat comprising a relatively hard glass-like valve body loosely fitting and guided in the outlet passage, a flat flexible valve on top of said valve body, a cork-like washer above said valve, a float above said cork-like washer, and means securing said valve parts together. 115

5. In a bottle construction, a bottle neck having an outlet passage and a valve seat surrounding said outlet passage, a valve normally engaging said valve seat and having a float on the upper portion thereof, and a 120 tubular guard above said valve loosely surrounding and guiding the float portion of the valve, said guard having an opening in the side thereof to prevent the accumulation of liquid while pouring which would have a 125 130

4
tendency to float the valve into engagement with its seat.

6. In a bottle construction, a bottle neck having an outlet passage and a valve seat surrounding said outlet passage, a valve normally engaging said valve seat and displaceable by pressure down into said outlet passage below the valve seat, a tubular guard above the valve and receiving the upper portion of the valve, said guard having a pocket in the under side of the top thereof, and an opening through said top, and a locking device normally seated in said pocket and displaceable out of said pocket by a flow 10 of liquid through the opening in the top.

7. In a bottle construction, a bottle neck having an outlet passage and a valve seat surrounding said outlet passage, a valve normally engaging said valve seat and having a float on the upper portion thereof, and a tubular guard above said valve loosely surrounding and guiding the float portion of the valve, said guard having an opening 20 therein to prevent the accumulation of liquid 25 while pouring which would have a tendency

to float the valve into engagement with its seat.

8. In a bottle construction a bottle neck having an outlet passage and a valve seat surrounding said passage and a valve for co-operation with said valve seat comprising a glass-like valve body guided in the outlet passage, a flexible valve on top of said valve body and extending beyond the rim of the same to engage the valve seat, a cork-like 30 float above said flexible valve and an up-standing stem integral with the valve body 35 engaging in the cork-like float to thereby secure all of the valve parts together.

9. As an article of manufacture, a bottle 40 valve comprising a glass-like valve body, a flat flexible valve resting on said valve body and extending out beyond the edges of the same, a cork-like float engaged on top of said flat flexible valve and an upstanding headed 45 post on the glass-like valve body engaged in the cork-like float to thereby fasten the parts of the valve structure together.
